(21) Appl. No.: **29/120,136**

The ornamental design for a glare reducing hood for a laptop computer monitor, as shown and described.

(22) Filed: **Mar. 15, 2000**

DESCRIPTION

(51) LOC (7) Cl. **14-02**

FIG. 1 is a perspective view of a glare reducing hood for a laptop computer monitor showing my new design;
FIG. 2 is a front elevational view thereof;

(52) U.S. Cl. **D14/449**

FIG. 3 is a side elevational view thereof, the opposite side being a mirror image;

(58) Field of Search D14/432, 439-40,

FIG. 4 is a rear elevational view thereof;

D14/448-9; 150/154-65; D18/12, 18; 348/832-5;
359/599, 601-10, 614

FIG. 5 is a top plan view thereof; and,

D311,912 S * 11/1990 Schmidt

FIG. 6 is a bottom plan view thereof.

D337,591 S * 7/1993 Buhyoff

The broken line drawing of a laptop computer and monitor in all views is for illustrative purposes only and forms no part of the claimed design.
